D19/33		

FIG. 1 is a side view of a wall mount trading card display device with protective cover;

FIG. 2 is a top view of a wall mount trading card display device with protective cover; and,

FIG. 3 is an exploded perspective view of the top, side and front for a wall mount trading card display device with protective cover in an alternate configuration.

The broken line showing is included for the purpose of illustrating portions of the "article" and forms no part of the claimed design. The broken line showing of "trading card protector case" depicts unclaimed environmental subject matter.
